Primary Examiner — Philip S Hyder(74) *Attorney, Agent, or Firm* — Adam R. Stephenson, Ltd.(57) **CLAIM**

The ornamental design for an applicator blade, as shown and described.

DESCRIPTION

FIG. 1 is front perspective view of an implementation of a blade coupled to an applicator;

FIG. 2 is a front perspective view of the blade of FIG. 1;

FIG. 3 is a front view of the blade of FIG. 1;

FIG. 4 is a back view of the blade of FIG. 1;

FIG. 5 is a left sided view of the blade of FIG. 1;

FIG. 6 is a right sided view of the blade of FIG. 1;

FIG. 7 is a top view of the blade of FIG. 1; and,

FIG. 8 is a bottom view of the blade of FIG. 1.

The even broken lines illustrate portions of the applicator blade in which the design is embodied that form no part of the claimed design. The uneven broken lines delineate unclaimed boundaries.
